UNITED STATES PATENT OFFICE.

GUSTAVE WENZELMANN, OF GALESBURG, ILLINOIS.

OPERATING MEANS FOR DRIVEN MECHANISMS.

1,118,980.

Specification of Letters Patent.

Patented Dec. 1, 1914.

Application filed October 23, 1911. Serial No. 656,158.

To all whom it may concern:

Be it known that I, GUSTAVE WENZELMANN, a citizen of the United States, and residing at Galesburg, in the county of Knox and State of Illinois, have invented a new and useful Improvement in Operating Means for Driven Mechanisms, of which the following is a complete specification.

The main objects of this invention are to provide a washing machine stand with novel means for supporting the wringer in the various positions required without interfering with wringer operating mechanism; to provide an improved construction whereby a single wringer may be employed with a plurality of washers and tubs and be shifted to its various operative positions without detaching it from its mountings; to provide a device in which the position of the wringer may be changed with but slight effort; to provide means for simultaneously driving the washers, or either one thereof while the other is at rest; to provide means for simultaneously operating a washer and the wringer, or both washers and the wringer; to provide a support for the wringer adapted to compensate for unevenness in the floor; and to provide a strong, cheap, and durable construction adapted to greatly lessen the labor ordinarily occasioned with such devices.

Concise stated, the objects of the invention are to generally improve the construction and increase the capacity, efficiency and utility of devices of this character.

A specific embodiment of the invention is illustrated in the accompanying drawings, in which:

Figure 1 is a front elevation of a washing machine, washing machine stand, and horizontally swinging wringer therefor embodied in this invention. Fig. 2 is a top plan view of the same with the wringer shown in its various operative positions. Fig. 3 is a section taken on line 3—3 of Fig. 1, showing the wringer mounting and operating mechanism in side elevation. Fig. 4 is a front elevation of the wringer mounting and operating mechanism. Fig. 5 is a section taken on line 5—5 of Fig. 4. Fig. 6 is a fragmentary plan view of the reversing mechanism for the wringer. Fig. 7 is a fragmentary side elevation of said reversing mechanism.

In the construction shown the stand or bench 1 has mounted thereon two washers, 2 and 3, and two tubs, 4 and 5, which are

conveniently arranged in the form of a square.

Journaled in suitable bearings beneath the top or platform of the bench is the transmission shaft 6 from which the washer and wringer mechanism are operated. A drive shaft 7 is also journaled in the bench, parallel with the transmission shaft, and is provided on its outer end with a drive pulley 8. On the inner end of the shaft 7 is a pinion 9 which meshes with a gear 10 on the shaft 6 to drive the latter shaft.

Loosely mounted on the shaft 6, at a point intermediate the tubs and washers, are beveled pinions 11 and 12, which are provided on their adjacent faces with clutch members 13 and 14, respectively, as shown best in Fig. 3. A bearing standard 15 has a fork 16 at its lower end, in the arms of which the shaft 6 is journaled. Said arms bear against the outer faces of said pinions and act to hold the pinions in position on the shaft 6. Said standard extends upwardly through the top of the bench to a point slightly above the level of the washers, and is provided with a laterally offset bearing 17 at its upper end in axial alignment with a bearing 18 in the fork 16. A shaft 19 is journaled in the bearings 17 and 18 and projects above the bearing 17, and is provided on its lower end with a beveled gear wheel 20 in mesh with the pinions 11 and 12.

The upper end of the bearing 17 is provided with a peripheral groove 21, and a wringer supporting arm 22 is provided on its end adjacent to the shaft 19 with a fork 23 adapted to engage in said groove. Mounted on the arm 22 above the fork 23 is a bearing 24. The upper end 25 of the shaft 19 is angular in cross section, and a beveled pinion 26 is mounted on the top of the bearing 24 and is provided with a stud shaft or pin 27 which is journaled in and projects through the bearing 24, and is provided in its lower end with an angular socket in which the end 25 of the shaft 19 loosely fits. Rigidly secured on the under side of the arm 22 is a brace 28 which projects downwardly and toward the shaft 19 and its end 29 is turned horizontally and is provided with an aperture through which the shaft 19 projects. A bracket 30 is secured on the standard 15 in position to support the end 29 of the brace, and is also provided with an aperture through which the shaft 19 projects.

The connection between the arm 22 and the standard 15 and shaft 19 permits the outer end of said arm to have sufficient vertical movement to compensate for any inequalities in the floor, and to facilitate swinging it to its various operative positions.

Mounted on the arm 22 is the wringer 31 having a shaft 32 which is journaled in a bearing 33 on the arm 22 and is provided on its outer end with a beveled pinion 34 in mesh with the pinion 26.

Extending upwardly from the bench 1 are posts 35, 36 and 37, which are positioned respectively to support the outer end of the wringer arm 22 when the wringer is in position to wring from the washer 2 to the tub 4, tub 4 to tub 5, and vice versa, and from the washer 3 to the tub 5. On the top of each post is a plate 38 having a down-turned flange 39 at its outer edge which is provided with a notch 40, and carried in the outer end of the arm 22 is a bolt 41 having a hook 42 at its lower end adapted to engage in the notch 40 when the arm is resting on the top of the post and hold the wringer rigidly in place. The upper end of the bolt is provided with a wing nut 43 adapted to draw the hook up into the notch.

For the purpose of reversing the wringer a clutch member 44 is slidably mounted on the shaft 6 intermediate the clutch members 13 and 14 and adapted to engage therewith to lock the pinions to the shaft 6. A bell-crank lever 45 is pivoted on a pin or shaft 46 extending downwardly from the top of the stand 1 and is provided with a fork 47 at one end which engages in a groove in the clutch member 44, and the other end of said lever 45 is provided with a slot 48.

Journalized in the legs 49 of the stand is a rock shaft 50, and journalized in the legs 51 is a rock shaft 52. Each rock shaft is provided with an upwardly directed arm 53 which arms are pivotally connected together by a bar 54. Extending upwardly from the bar 54 is a bar 55 which is provided with an upwardly directed pin 56 in its upper end which engages in the slot 48. On each end of the shafts 50 and 52 is a treadle 57 in position for the operator to operate with the foot when wringing from either of the washers or the tubs. When the treadle is thrown in one direction the bell-crank lever 45 shifts the clutch member 44 to engage the clutch member 13 and when thrown in the opposite direction the clutch member 44 is shifted to the clutch member 14 thereby reversing the drive of the wringer. For the purpose of normally holding the clutch member 44 out of engagement with both the clutch members 13 and 14 coiled springs 58 are connected to the forked end of the lever 45 and to the stud pins 59 on the under side of the stand top.

For the purpose of operating the washers the shaft 6 is provided with a clutch member 60 which is rigidly secured thereon, and with a cup shaped pitman 61 which is slidably secured on said shaft and, is provided with a clutch member 62 adapted to engage the clutch member 60. A bar 63 is pivoted at its upper end to a bracket 64 supported beneath the top of the stand and is connected intermediate its ends to the pitman 61 by means of a link 65. A lever 66 is pivoted to a stud shaft 67 carried on the top of the stand intermediate the washers 2 and 3. A link 68 pivotally connects the lower end of the bar 63 with the lower end of the lever 66. Arms 69 and 70 are pivoted to the upper end of the lever 66 and are provided at their opposite ends with a hook 71 adapted to engage the rack 72 of the washer mechanism. The pitman 61 is adapted to slide on the shaft 6 to throw the clutch member 62 into and out of engagement with the clutch member 60.

The operation of the construction shown is as follows: When the wringer is in the position shown in Fig. 1 and the pulley 8 is driven in the direction indicated by the arrow in Fig. 2, if the clutch member 44 is thrown into engagement with the clutch member 14, the wringer will be turned in a direction to wring from the washer 2 into the tub 4. The wringer is held rigidly in place by means of the bolt 41 which engages the plate 38 on the post 35. When it is desired to wring from the tub 4 to the tub 5, or vice versa, the wringer arm 22 is released from the post 35 and swinging on the shaft 19 as a center until its outer end rests on the post 36. In this position clothes may be wrung from either of the tubs 4 or 5 into the other by simply shifting the clutch member 44. When it is desired to wring from the washer 3 to the tub 5 the wringer arm is swung around to the post 37.

In shifting the wringer to its various positions the driving mechanism therefor is in no way disconnected or interfered with since the pinion 34 simply travels around on the pinion 26. The yielding connection between the arm 22 and the standard 15 and shaft 19 permits the outer end of the arm 22 to have sufficient vertical movement to enable it to be easily placed on or removed from the supporting posts therefor.

The treadles 57 are so situated that the operator may easily shift the clutch member 44 in any of the positions in which the operator is required to stand when wringing the clothes. Either of the washers may be operated if desired while the other is at rest by simply disconnecting the bar 69 or 70 from the operating mechanism of the one not in use.

While but one specific embodiment of the invention has been herein shown and de-

scribed it will be understood that many details of the construction shown may be varied or omitted without departing from the scope of the claims.

5 I claim:

1. In a device of the character described, a standard, a horizontally swinging arm at the top thereof, a fork on the arm, loosely engaging the top of the standard, a shaft 10 journaled on the standard, a stud-shaft journaled on the arm and loosely coupled to said shaft, a gear on the stud shaft, an operative mechanism mounted on the arm and driven by said gear, and means for supporting the outer end of said arm.
2. In a device of the character described, a stand, a standard thereon, a shaft journaled on the standard, means adapted to rotate the shaft in either direction, an arm pivotally 20 mounted on the standard and adapted to rotate about said shaft as a center, an operative mechanism mounted on the arm and

adapted to be driven from said shaft, posts on the stand, adapted to support the outer end of the arm, and means for locking the 25 outer end of the arm to the posts.

3. A device of the nature described comprising a stand, an operative mechanism, means adapted to support it above the stand and adapted to swing in horizontal arc, a shaft journaled at the axis of movement of said mechanism and adapted to operate it, clutch mechanism and means associated therewith adapted to drive said shaft in either direction, and means for operating 35 the clutch mechanism.

In testimony whereof I have hereunto subscribed my name in the presence of two witnesses.

GUSTAVE WENZELMANN.
